Filed Mar. 16, 1962, Ser. No. 69,309

Term of patent 14 years

(CL. D13—1)

FIG. 1.

FIG. 2.

FIG. 3.

FIG. 4.

FIG. 5.

FIG. 6.

FIG. 7.

FIGURE 1 is a front elevation of a telephone booth showing my new design;

FIGURE 2 is a right side elevation thereof;

FIGURE 3 is a top plan view thereof;

FIGURE 4 is a rear elevation thereof;

FIGURE 5 is a section taken on line 5—5 of FIGURE 1;

FIGURE 6 is a perspective showing the front and right side of the telephone booth; and

FIGURE 7 is a perspective showing the rear and left side of the telephone booth.

The left side of the telephone booth is the same in appearance as the right side shown in FIGURE 4.

The essential features of my new design reside in the portions shown in full lines.

The telephones shown in broken lines in FIGURES 5, 6 and 7 are included for illustrative purposes only.

I claim:

The ornamental design of a telephone booth, as shown and described.
